UNITED STATES PATENT OFFICE.

GEORGE B. KNIGHT, OF CAMDEN, NEW JERSEY.

HEAD-GUARD ATTACHMENT FOR CAPS.

1,345,933.

Specification of Letters Patent.

Patented July 6, 1920.

Application filed August 22, 1919. Serial No. 319,064.

To all whom it may concern:

Be it known that I, GEORGE B. KNIGHT, a citizen of the United States, residing in the city and county of Camden, State of New Jersey, have invented a new and useful Head-Guard Attachment for Caps, of which the following is a specification:

My invention consists of an attachment for a cap designed to protect the wearer thereof from injurious blows due to objects falling thereon.

It consists also of means for insulating said attachment so that electrical wires or other devices of electric transmission which may come in contact with said attachment will be prevented from shocking the wearer of the cap.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a central vertical section of a cap and the attachment therefor embodying my invention.

Fig. 2 represents a top plan view of the attachment, and a portion of a cap to which it is applied.

Fig. 3 represents a perspective view partly broken away of a portion of the attachment.

Similar numerals of reference indicate corresponding parts in the figures.

Referring to the drawings.

1 designates a cap of ordinary construction, 2 designates a guard for protecting the head of the wearer of the cap from injurious blows occasioned by bolts, or other articles dropping from above in a factory or elsewhere, and striking the guard and consequently the head of the wearer, said guard extending across the underside of the top of the crown portion of the cap and being somewhat of the form of a sack consisting of the bottom piece 3 of fabric, and an in-turned rim 4 at the top of the periphery thereof. In said sack is placed a pad 5 of wire net or mesh, or other suitable material of substantially or relatively rigid material, the rim 6 uniting the peripheral portion of said net or mesh, thus strengthening said net or mesh. In said sack is placed also a mat 7 of steel fiber, wool, asbestos or other pliable material somewhat elastic and not liable to be affected by heat, which latter oth-

erwise would be communicated to the cap, said mat forms a yielding cushion for said pad.

The mat is placed on the bottom piece of 60 the sack and the pad is seated on said mat, and the peripheral portions of the pad and mat are placed in the peripheral space of the sack between said bottom piece and the peripheral rim 4, and so the guard is re- 65 tained in the sack assisted by suitable stitches of wire, thread, etc. The sack is rested under the top portion of the crown of the hat and sustained therein.

Depending from the periphery of the sack 70 and secured thereto is the rim 8 which is adapted to embrace the peripheral portion 9 of the crown of the cap, and the exterior of the band 10 of the cap to which band said rim may be secured by stitches or other 75 means, thus holding the guard in position on the cap.

11 designates a cover for the guard, the same being formed of suitable fabric or other material and adapted to conform to 80 the form of the crown of the cap, it inclosing the guard and concealing the same without interfering with the operation of the guard, it being seen that the pad and mat form a cushion in the sack which in the 85 event of articles dropping on the guard will prevent the blows or force from striking the head of the wearer through the crown, the pad being of open work or mesh and being sufficiently strong to prevent the same from 90 being broken through by said articles without being materially heavy, while the mat portions of which may enter the interstices of the pad owing to its pliable nature, forms a yielding cushion on which said pad is im- 95 posed and so receives any blow to which the latter may be subjected, the material of which the mat is composed being also of a nature that prevents the heating of the crown of the cap.

Imposed on the top of the pad and passing under the top rim 4 of the sack is the sheet or piece 12 of insulating material which may continue from the periphery of the sack downwardly around the periphery 105 of the crown of the cap to the exterior of the band of the cap where it is inclosed in the folded portion 13 of the bottom of the rim 4, it being seen that should the cap strike electric conductors or devices, or the 110 latter come in contact with the cap the piece 11 will prevent the current or shocks from

reaching the head of the wearer. The mesh or open like structure of the pad and the loose but intermixed nature of the mat are not heavy in their natures, the effect of 5 which is evident.

Having thus described my invention what I claim as new and desire to secure by Letters Patent, is:—

1. A head guard for a cap consisting of 10 a base pad of mesh or open like structure of relatively rigid material, and a cushion of pliable material on which said pad is imposed, said guard being adapted to extend across the underside of the top of the crown 15 portion of the cap.
2. A head guard for a cap consisting of a pad of mesh or open-like structure of relatively rigid material, a mat of pliable material on which said pad is imposed, and a 20 sack adapted to contain said mat and pad and to be fitted to the crown of the cap.
3. A head guard for a cap consisting of a pad of mesh or open-like structure of relatively rigid material, a mat of pliable material on which said pad is imposed, and a 25 sack adapted to contain said mat and pad and to be fitted to the crown of the cap, said sack having a depending rim which is adapted to be fitted around the side of said crown.

- 30 4. A head guard for a cap consisting of a pad of mesh or open-like structure of rela-

tively rigid material, and a rim therefor, a mat of pliable material on which said pad is imposed, and a sack adapted to contain said mat and pad and to conform to the crown of a cap to which it is secured and to inclose 35 said rim.

5. A head guard for a cap consisting of a pad of mesh or open-like structure of relatively rigid material, a rim therefor, a mat 40 of pliable material on which said pad is imposed; a sack adapted to contain said mat and pad and to conform to the crown of a cap to which it is secured, and a cover for 45 said guard attachable to the cap.

6. A head guard for a cap consisting of a pad of mesh or open-like structure of relatively rigid material, a mat of pliable material on which said pad is imposed, a sack 50 adapted to contain said mat and pad, said guard being attachable to the cap, and a cover for said guard adapted to be retained 55 in the cap.

7. A head guard for a cap of the character stated, the same being provided with 51 means for electrically insulating the same from the cap.
